TYPE-WRITING MACHINE.

975,099.

Specification of Letters Patent. Patented Nov. 8, 1910.

Application filed July 16, 1909. Serial No. 507,920.

To all whom it may concern:

Be it known that I, Cllo B. Yaw, citizen of the United States, and resident of Arlington, in the county of Hudson and State of New Jersey, have invented certain new and useful Improvements in Type-Writing Machines, of which the following is a specification.

My invention relates to typewriting machines and more particularly to line lock and margin stop mechanism for such machines, and the main object of the invention is to provide a simple and efficient construction of the character specified.

To the above and other ends which will hereinafter appear, my invention consists in the features of construction, arrangements of parts and combinations of devices to be hereinafter described and particularly pointed out in the appended claims.

In the accompanying drawings wherein like reference characters indicate corresponding parts in the various views, Figure 1 is a vertical front to rear sectional view showing a sufficient number of parts of one form of typewriting machine to illustrate my invention in its embodiment therein. Fig. 2 is a bottom view of the same. Fig. 3 is a fragmentary bottom view showing portions of the line lock mechanism, the parts being shown in the locked position. Fig. 4 is a fragmentary detail front view of a portion of the line lock and margin stop mechanism. Fig. 5 is a fragmentary detail vertical sectional view of a portion of the line lock mechanism. Fig. 6 is a fragmentary vertical sectional view showing the final margin stop in coöperation with the stop on the frame. Fig. 7 is an enlarged detail transverse sectional view taken through the stop carrying rod on the carriage and showing the means for securing one of the adjustable stops on the stop rod.

I have shown my invention embodied in the present instance in a front-strike typewriting machine but from certain aspects of the invention it may be embodied in various styles of typewriting machines.

The frame of the machine comprises side plates 1 united by front and rear cross plates 2 and 3 respectively. The side plates support fixed grooved guide rails 4 which coöperate with anti-friction balls or rollers 5 which are likewise received in oppositely grooved rails 6 carried by a carriage truck 7.

The carriage is thus mounted to travel from side to side of the machine in the usual manner. A platen frame 8 is pivoted at 9 to swing from the full line position shown in Fig. 1 to the dotted line position for purposes which will hereinafter appear. In the normal position of the platen frame, shown in full lines in Fig. 1, depending feet 10 at the forward side of the platen frame bear upon the truck and support the platen frame. Pins 11 project laterally from the end plates of the platen frame and coöperate with upwardly projecting ears 12 on the truck when the platen frame is swung back to the dotted line position, in order to limit the backward movement of the platen frame and support it in its swung-back position. A cylindrical platen *a* is supported to turn in bearings in the platen frame and is moved with the platen frame during the swinging movement thereof.

Perforated guide plates 13 are supported on the side plates 1 and receive key stems 14 of the printing keys 15. The lower ends of the key stems are received in perforations 16 in a fixed horizontally disposed guide plate 17 secured at its ends to the side plates 1 of the machine. The guide plates 13 and 17 thus constitute means for guiding the key stems in their vertical movements. Each key stem 14 is connected by a laterally projecting headed pin 18 with an angular type bar actuating lever 19, the pin being received in a slot 20 in the forwardly extending horizontally disposed arm of the lever. Each pin is carried by and projects laterally from a sleeve 21 connected to its key stem by a set screw 22. The angular levers 19 are pivoted at 23 to individual hangers 24 secured by screws 25 to a segment 26 fixed at its ends to the side plates of the machine. Contractile restoring springs 27 are each connected at one end to an upright arm of an angular actuating lever and at its opposite end to a fixed plate 28. The upright arm of each angular lever is pivotally connected to a pull link 29 pivoted at its rear end as at 30 to the heel of a type bar 31 pivoted at 32 to a type bar hanger 33 secured to a type bar segment 34. The type bars are all supported at their forward ends on a pad 35 and move upwardly and rearwardly to strike against the front face of the platen *a*.

A horizontally disposed locking plate 36

is pivotally connected by shouldered screws 37 to the lower ends of parallel supporting links 38 pivoted on shouldered screws 39 at the upper ends thereof to the side plates of the machine. This locking plate is provided with perforations 40 which when the locking plate is in the normal position are adapted to register with the openings 16 in the lower fixed guide plate and with the key stems 10 which project therethrough as indicated in Fig. 2. From an inspection of Fig. 1 it will be seen that when the locking plate is in the normal position the parallel guide links 38 are disposed at a slight angle and afford a 15 horizontal forward movement of the locking plate to the position shown in Fig. 3 where the openings 40 are thrown out of register with the lower ends of the key stems and with the guide openings 16 in the fixed 20 guide plate, thereby bringing the full body portion of the locking plate opposite to the lower ends of the key stems to prevent a depression of any of the key stems and thus lock the printing keys against actuation. 25 It will be observed from an inspection of Fig. 3 that at this time the parallel supporting links 38 are substantially vertically disposed or are dead centered so that pressure exerted by any of the key stems on the locking plate presses the locking plate against the dead centered links by a direct downward movement so that no movement of the locking plate can take place.

The locking plate is moved into and out 30 of locking position by the following means: A rearwardly extending link 41 is pivoted at its forward end to the locking plate on a shouldered pivot screw 42. The rear end of the link is pivoted by a shouldered pivot screw 43 to a crank arm 44 fixed to an upright shaft 45 supported in bearings 46 secured to the left-hand side plate 1 by screws 47. The upper end of the shaft has a collar 48 fixed thereto by a set screw 49, the collar being 45 supported upon the upper bearing 46 and thus supporting the upright shaft 45 in place. A crank arm 50 is formed as a part of the collar and extends forwardly therefrom and is slotted at its forward end as indicated at 51 for the reception of a pin 52 which projects from a rod or shaft 53 mounted in bearings 54 for longitudinal and turning movement. The bearings 54 project from brackets 55 secured by screws 56 55 to the forward fixed carriage rail 4. A coiled spring 57 surrounds the rod 53 and is secured at one end in an opening in a sleeve 58 connected by a set screw 59 with the rod. The opposite end of the coiled spring is secured in an opening in one of the bearings 54. This spring exerts a pressure to normally maintain the rod 53 toward the right 60 where its right-hand end bears against the right-hand side plate 1 of the frame and 65 limits the movement of the rod in this direc-

tion. The spring also exerts a force to turn the rod 53 in its bearings to the position shown in Figs. 1 and 2 for purposes which will hereinafter more clearly appear. A stop 60 is secured about midway of the shaft 70 or rod 53 by pins 61 which pass through sleeves formed on the stop and through the shaft to lock the stop on the shaft. The stop 60 projects rearwardly from the shaft 53 for coöperation with line lock and margin 75 stops carried by the carriage as shown in Fig. 1.

A detachable stop rod 62 is secured by screws 63 to the carriage and is located beneath the platen. The forward face of this 80 stop rod is provided with indices 64 which correspond to the carriage scale. A line lock stop 65, a final line lock stop 66, a margin stop 67 and a final margin stop 68 are adjustably secured to the stop rod. The 85 fastening means for securing each of the four stops 65, 66, 67 and 68 to the stop rod 62 is the same so that the description of the fastening means for one of these stops will suffice for all of them. The stop rod is provided with teeth 69 on the bottom side thereof as shown in Fig. 4; and from an inspection of Fig. 7 it will be seen that a hook-like locking member 70 forms part of a stem 71 threaded at 72 for coöperation with an 90 internally threaded finger piece or cap 73 by which the locking device 70 is actuated. A coiled expansion spring 74 is received in an opening 75 in the stop in which the stem 70 and finger piece 73 operate. The coiled 100 spring 74 surrounds the stem 71 and bears at its upper end against the lower edge of the cap or finger piece 73 and bears at its lower end against the lower wall of the opening 75. The spring thus exerts the 105 force to maintain the locking member 70 seated between the teeth 69 of the stop rod to lock the stop in place on the rod. Each of the stops is cut out to provide an opening 110 to receive the stop rod so that each stop surrounds the stop rod on three sides, leaving the fourth side of the opening free or open to provide a withdrawal of the stops from the rod when the rod is removed from the machine. When the stop rod is in place in 115 the machine the forward faces of the stops just clear the forward rail 6 of the carriage and a displacement of each of the stops from the rod is thereby prevented, although the stops may be adjusted longitudinally of the 120 rod when the locking members or latches 70 are released from the teeth 69. The line lock stop 65 is provided with a depending portion 76 having a flat vertical face 77 on the left-hand side thereof, the right-hand 125 side of the projection 76 being beveled as indicated at 78. The construction therefore is such that in the movement of the carriage from right to left the flat face 77 of the projection 76 will be brought into engagement 130

with the stop 60 to effect a movement of it together with its rod 53 to the left until the left-hand end of the rod 53 abuts the left-hand side plate 2 of the frame. This movement of the rod 53 is effected against the pressure of the spring 57 and is effective to turn the upright rock shaft 45 through the crank arm 50. An oscillation of the rock shaft 45 effects a forward movement of the link 41, thus moving the locking plate from the position shown in Fig. 2 to that indicated in Fig. 3 where the openings 40 in the locking plate are thrown out of register with the lower ends of the key stems, thus locking the key stems and the type actions against actuation. In the movement of the carriage just described the projection 76 first meets a trip b (Fig. 4) connected with a suitable alarm to warn the operator of the approach 20 of the carriage to the end of a line.

I have provided a line lock releasing means in order to enable the operator to write one or more characters to complete a word or insert a hyphen after the printing keys have been locked against actuation. This line lock release comprises a release key 79 connected to a key stem 80 which in turn is pivotally connected to the forward end of a horizontal arm of an angular lever 81 pivoted to a stud which projects inwardly from the left-hand side or end plate 1 of the frame. The upright arm of this angular lever is connected with a pull link 82 which has its rear end pivotally connected to a depending crank arm 83 secured to the rod or shaft 53. By depressing the release key 79 a forward movement of the crank arm 83 is effected which is operative to turn the rod 53 so that the stop 60 will move downwardly and clear the projection 76 on the margin stop 65 as shown in Fig. 6, thus releasing the stop 60 from control of the margin stop and allowing the spring 57 to restore it to normal position by moving the stop rod 53 longitudinally to its normal position. The effect of this movement is to restore the locking plate to its normal position shown in Figs. 1 and 2 to release the printing keys. From an inspection of Fig. 3 it will be observed that the slot 51 in the crank arm 50 extends at right angles to the axis of the shaft or rod 50 when the locking plate is in the locked position so that the rod 53 at this time may be turned without affecting the arm 50 and without being affected by it. After the line lock has been released and one or more characters have been written and the margin stop 65 passes to the left of the stop 60, pressure on the release key 79 having been released, the stop 60 will again be moved into the path of the projection 76. If, however, the carriage be moved to the right at this time the beveled face 78 will depress the stop 60 against the pressure of its spring 57 so that the stop 60 at

this time offers no obstruction of the movement of the carriage to the right. The final line lock stop 56 has a depending contact portion 84 longer than the projection 76. The length of this projection is such that the swinging movement of the stop 60 is insufficient to clear it of the projection 84 so that the line lock release key is ineffective to clear the final stop 66. This stop co-operates with the stop 60 in the same manner as the line lock stop 65, except that the stop 66 cannot pass beyond the stop 60. The margin stop 67 has a depending projection 85 which co-operates with the stop 60 in substantially the same manner as the line lock stop 65 does, except that when the margin stop contacts with the stop 60 the right-hand end of the rod 53 abuts the right-hand end plate 1 of the frame as shown in Fig. 2, and a longitudinal movement of the rod 53 to the right at this time is therefore prevented and the carriage will be arrested in its movement to the right. A depression of the release key, however, is effective to turn the stop 60 out of the path of the projection 85 on the margin stop to enable the operator to move the carriage farther to the right to write within the margin if desired. In the return movement of the carriage a beveled face 86 on the margin stop contacts with the stop 60 and turns it to one side to enable the carriage to travel freely past it. The final margin stop 68 is provided with a depending projection 87 which is longer than the projection 85 and cannot be cleared by the stop 60 when the release key 79 is depressed.

From an inspection of Figs. 1 and 2 it will be seen that the margin and line lock stop are carried by the carriage and are situated beneath the platen where ordinarily they would be inaccessible to the operator. However, by providing a platen frame which can be swung back from the full to the dotted line positions shown in Fig. 1 the platen and the platen frame together with all the other parts carried by the latter are removed from the position where they constitute an obstruction, and access is readily given to the margin and line lock stops in order that they may be quickly set from the front of the machine. After the stops have been set the platen frame is turned down to the normal position shown in full lines where the margin stops are out of view and occupy a space where they cannot be easily deranged or broken. In short, the swinging of the platen frame covers and uncovers the margin and line lock stops so that in one case the stops are not accessible to the operator and in the other case they are.

It will be seen that by inclining the supporting links 38, when the locking plate is in the normal position and having the links move to the dead centered position when the line lock mechanism is actuated, I am en-

abled to utilize the weight of the locking plate itself to move it to locking position so that but little power is required to actuate the line lock mechanism from the traveling carriage.

The carriage construction *per se* is not claimed herein. claims to such construction being embodied in my application, Serial No. 528,964, filed Nov. 19th, 1909.

10 Various changes may be made without departing from the spirit and scope of my invention.

What I claim as new and desire to secure by Letters Patent, is:—

15 1. In a typewriting machine, the combination of a carriage, printing instrumentalities, key actuated devices therefor including key stems arranged in different rows, a locking plate adapted to be thrown into and

20 out of the paths of all of said key stems, and automatically actuated means for moving said locking plate into the paths of the key stems when the carriage reaches the end of a line.

25 2. In a typewriting machine, the combination of a carriage, printing instrumentalities, key actuated devices therefor including key stems arranged in different rows, a locking plate with perforations therein, said plate being adapted to be moved to throw the perforations into and out of register with said key stems, and automatically actuated means for moving said locking plate into the paths of the key stems when the

35 carriage reaches the end of a line.

3. In a typewriting machine, the combination of a carriage, printing instrumentalities, key actuated devices therefor including key stems, a locking plate mounted beneath the lower ends of said key stems, parallel links on which said locking plate is mounted and which are dead centered when the locking plate is in the locking position, and means controlled by the movement of the carriage for throwing said locking plate into and out of the paths of said key stems.

4. In a typewriting machine, the combination of a carriage, printing instrumentalities, key actuated devices therefor including key stems, a locking plate with perforations therein, said plate being adapted to be moved to throw the perforations into and out of register with said key stems, parallel links on which said locking plate is mounted and which are dead centered when the perforations are out of register with the key stems, and automatically actuated means controlled by the movement of the carriage, for throwing said locking plate into and out of the paths of said key stems.

5. In a typewriting machine, the combination of a carriage, printing instrumentalities, key actuated means for operating the same including vertically movable key stems, guides for said key stems, a horizontally dis-

posed locking plate situated beneath the key stems and perforated to allow the key stems to pass therethrough when the perforations are in register with the key stems and adapted to prevent a full depression of the key stems when the perforations are out of register with said key stems, and line lock mechanism controlled by the movement of the carriage for moving said locking plate horizontally into and out of locking position.

6. In a typewriting machine, the combination of a carriage; printing instrumentalities; key actuated means for operating the same including vertically movable key stems; guides for said key stems; a horizontally disposed locking plate situated beneath the key stems and perforated to allow the key stems to pass therethrough when the perforations are in register with the key stems and adapted to prevent a full depression of the key stems when the perforations are out of register with said key stems; and line lock mechanism controlled by the movement of the carriage for moving said locking plate horizontally into and out of locking position, said line lock mechanism comprising a vertically disposed rock shaft, a link between said rock shaft and locking plate, a rod movable in the direction of the travel of the carriage, said rod being operatively connected with said rock shaft, and means on the carriage for effecting a longitudinal movement of said rod.

7. In a typewriting machine, the combination of a carriage; printing instrumentalities; key actuated means for operating the same including vertically movable key stems; guides for said key stems; a horizontally disposed locking plate situated beneath the key stems and perforated to allow the key stems to pass therethrough when the perforations are in register with the key stems and adapted to prevent a full depression of the key stems when the perforations are out of register with said key stems; and line lock mechanism controlled by the movement of the carriage for moving said locking plate horizontally into and out of locking position, said line lock mechanism comprising a vertically disposed rock shaft, a link between said rock shaft and locking plate, a rod movable in the direction of the travel of the carriage, said rod being operatively connected with said rock shaft, a line lock stop on said rod, a co-operative line lock stop on the carriage, and hand actuated line lock releasing means for rocking said longitudinally movable rod to clear the stops and thus release the line lock mechanism.

8. In a typewriting machine, the combination of a carriage, an adjustable line lock stop carried by the carriage, a longitudinally movable and turning rod carried by the frame of the machine, a line lock stop fixed thereto, an upright rock shaft operatively

- connected to said rod to be turned thereby, a locking plate, and intermediate connecting means between said locking plate and said rock shaft.
5. 9. In a typewriting machine, the combination of a carriage, an adjustable line lock stop carried by the carriage, a longitudinally movable and turning rod carried by the frame of the machine, a line lock stop fixed thereto, an upright rock shaft operatively connected to said rod to be turned thereby, a locking plate, intermediate connecting means between said locking plate and said rock shaft, and hand actuated means operable at will to turn said rod to clear the stops and thus release the line lock mechanism.
10. 10. In a typewriting machine, the combination of a carriage, an adjustable line lock stop carried by the carriage, a longitudinally movable and turning rod carried by the frame of the machine, a line lock stop fixed thereto, an upright rock shaft operatively connected to said rod to be turned thereby, printing key stems, a locking plate which co-acts directly with said key stems to lock them against depression, and intermediate connecting means between said locking plate and said rock shaft.
15. 11. In a typewriting machine, the combination of a carriage, an adjustable line lock stop carried by the carriage, a longitudinally movable and turning rod carried by the frame of the machine, a line lock stop fixed thereto, an upright rock shaft operatively connected to said rod to be turned thereby, printing key stems, a locking plate which co-acts directly with said key stems to lock them against depression, intermediate connecting means between said locking plate and said rock shaft, and hand actuated means operable at will to turn said rod to clear the stops and thus release the line lock mechanism.
20. 12. In a front strike typewriting machine, the combination of a horizontal truck comprising front and rear rails, a platen frame pivoted to the rear side of said truck to swing thereon, a platen in said frame, and an adjustable stop carried by said truck between the forward and rear rails thereof and accessible for adjustment by swinging the platen frame and platen upwardly and rearwardly on said truck.
25. 13. In a typewriting machine, the combination of key stems arranged in different rows, a carriage, a line lock stop, a final line lock stop, a margin stop, a final margin stop, all of said stops being carried by the carriage, a co-operative stop mounted on the frame of the machine, and a locking plate connected to said co-operative stop and co-operative directly with said key stems to lock them against depression.
30. 14. In a typewriting machine, the combination of key stems arranged in different rows, a carriage, a line lock stop, a final line lock stop, a margin stop, a final margin stop, all of said stops being carried by the carriage, a co-operative stop mounted on the frame of the machine for movement in the direction of the travel of the carriage and transversely thereto, a locking plate connected to said co-operative stop and rendered co-operative directly with said key stems to lock them against depression, and hand actuated means operable at will for clearing the co-operative stop and said margin or line lock stop but ineffective to clear the co-operative stop and the final stops.
35. 15. In a typewriting machine, the combination of key stems arranged in different rows, a carriage, a line lock stop, a final line lock stop, a margin stop, a final margin stop, all of said stops being carried by the carriage, a co-operative stop mounted on the frame of the machine for movement in the direction of the travel of the carriage and transversely thereto, a locking plate connected to said co-operative stop and rendered co-operative directly with said key stems to lock them against depression, and hand actuated means operable at will for clearing the co-operative stop and said margin or line lock stop but ineffective to clear the co-operative stop and the final stops.

Signed at the borough of Manhattan, city of New York, in the county of New York and State of New York this 15th day of July A. D. 1909.
